(57) **CLAIM**

The ornamental design for an auxiliary tool for sticking film, as shown and described.

DESCRIPTION

FIG. 1 is a front, right and top perspective view of an auxiliary tool for sticking film, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right-side elevation view thereof.

FIG. 7 is a top plan view thereof.

FIG. 8 is a bottom plan view thereof; and,

FIG. 9 is a partial enlarged view of an area labeled 9 in FIG. 1 comprising a bevel corner.

The broken lines shown in the drawings are included for the purpose of illustrating portions of the auxiliary tool for sticking film that form no part of the claimed design.
